CORPORATION OF NEW JERSEY.

CHUCK-ACTUATING MECHANISM.

No. 826,501.

Specification of Letters Patent.

Patented July 17, 1906.

Application filed September 19, 1904. Serial No. 225,081.

To all whom it may concern:

Be it known that I, BENGT M. W. HANSON, a citizen of Sweden, residing at Hartford, in the county of Hartford and State of Connecticut, have invented certain new and useful Improvements in Chuck-Actuating Mechanism, of which the following is a specification.

This invention relates to chuck-operating mechanism, and has for its object the provision of compact devices for causing the chuck to hold the stock.

A further object of the invention is the provision of pneumatic devices for operating the chuck, as will be hereinafter explained.

15 A further object of the invention is the provision of means whereby the grasping power of the chuck may be regulated.

My improved mechanism is actuated by fluid—such, for instance, as compressed air—and comprises in the preferred form shown a cylinder and multiple pistons in said cylinder, thereby affording a large surface for the fluid to act upon, as hereinafter set forth. In this way the usual single cylinder of large diameter is dispensed with, and as the spindle upon which said cylinder is mounted is subject to reversal while running at high speed the momentum thereof causes objectionable strains upon the driving mechanism, which strains are obviated by the present construction.

In the accompanying drawings, Figure 1 is a longitudinal vertical section of the head of a lathe provided with my improved chuck-actuating mechanism. Fig. 2 is a sectional view, on a larger scale than Fig. 1, illustrating the air connection.

Like characters designate similar parts throughout both the views.

Referring to the drawings, the numeral 5 designates the head of a lathe which is provided with the usual bearings 6 6' to receive a hollow spindle 7, driven by pulley 8, on the hubs of which are mounted loose pulleys 9 9'. A cylinder 10 is fitted to the end of rotary spindle 7, the latter being slightly reduced at its rear end to form a shoulder 11, against which the end of the cylinder abuts, said cylinder being held in place by a screw 12. Fitted within the cylinder 10 are three pistons 13 13' 13", as shown in Fig. 1, although a greater or less number may be employed without departure from the invention, and said pistons are actuated by air or other mo-

tive fluid supplied from a shaft 14, tubular for a portion of its length, as at 14', the tubular portion being provided with ports 16 16' 16", through which air is admitted to the cylinder 10 to operate the pistons and acts between piston 13 and the inner end of the cylinder 10, piston 13', and the partition 17 and 6c piston 13" and the partition 18.

For convenience in assembling the parts the cylinder is bored out at different internal diameters for the successive pistons.

Partitions 17 18 are fitted in place against 65 shoulders on the inner wall of the cylinder, so that they may receive the thrust of the motive fluid without being displaced, and they are secured against rotation with relation to the cylinder by screws 17' 18'.

70 All the pistons are keyed to shaft 14 and are secured against longitudinal movement on said shaft by the shoulder 19 and nut 20. Each piston consists of a web portion *a* and an extended hub *b*, the hubs passing through 75 the partitions and end of the cylinder, as shown in Fig. 1, and the hub of piston 16 abutting against the shoulder 19 aforesaid.

Designated by 21 is a tubular draw-in spindle provided with a head 21' at its end, said head having a T-slot to receive a similarly-shaped portion on the end of shaft 14, as indicated by 22, whereby no binding action, due to the possible improper alinement of the parts, will affect the action of the pistons. A 80 spring 23, always under tension, acts against the T-head of the shaft 14 and against the inner wall of the cylinder 10 to force the tubular spindle 21 forward, and thereby release the chuck 21' (shown as of the collet variety) 90 carried by said spindle.

A stationary collar 25 is mounted on the reduced end 24 of the tubular shaft 14, and said collar has an internal groove 26, to which fluid is conducted by the pipe 15. The fluid 95 then passes through a port 27 to the inner side of the shaft 14. Mounted on each side of the collar 25 are hardened washers 28 29, respectively, and a split clamp-nut 30 is provided, so that wear of the parts may be taken up.

When using hollow stock, the grasping power of the chuck due to the action of all of the pistons will tend to crush the same, and therefore provision is made whereby one or more of the pistons may be cut out of action. 105 To accomplish this result, an adjustable valve

31 is secured to a rod 32, having an enlarged threaded portion 33 screwed into the end of the tubular shaft 14, and therefore constituting a plug for the same. The valve 31 is adjustable along the rod 32 and may be secured at any point of adjustment by a screw 34, entering any one of a series of openings 35 in said rod. As will be readily evident, this valve may be adjusted along the rod to close 10 any of the ports desired, and therefore throw certain of the pistons out of action.

Should the stock vary in diameter throughout its length or be slightly different in any way from standard stock, the chuck in use is 15 adapted to receive, or should it have an uneven surface (like, for instance, rough cast-iron) the series of pistons is of great value in causing the chuck-jaws to close upon said stock under multiplied pressure, and thus 20 firmly to grasp the same.

By retracting the screw 33 and its attached rod 32 the valve 31 may be withdrawn through the bore of the tubular shaft 14, to be reset when it is desired to operate one or 25 more of the pistons. In Fig. 1 the valve is shown in position to cut off the rear piston 16, but when it is desirable to operate all the pistons the valve will be adjusted to the inner end of the rod 32, the bore of the shaft 14 30 extending inward far enough to enable the valve to be seated beyond the port 16. (See Fig. 1.)

To prevent the cushioning effect of air between the inner piston of the series and the 35 cylinder 10, a port 35^a is provided, which acts as an air-vent. A pin 36 is fastened in the piston 13 and enters an opening 36' in the head of the cylinder 10, and thus acts as a clutch to transmit the motion of the cylinder 40 10, which is secured to the spindle 7, to the piston 13, shaft 14, and the remaining pistons of the series. This clutch-pin is located at a distance from the axis of the cylinder 10, so 45 that when the spindle is reversed substantially no shock occurs in rotating the pistons.

While my invention is shown applied to a common form of lathe-head, it is distinctly to be understood that it is not limited thereto, for it is applicable as a means for actuating 50 chucks of any suitable kind and may be applied to any desired machine.

Changes may be made in the form and proportion of the parts, and they may be disposed either horizontally, vertically, or otherwise 55 without departure from the invention.

Having thus described my invention, what I claim is—

1. The combination, with a chuck, and its support, of a series of pistons for actuating 60 said chuck; a compartment-cylinder carried by the support, and having a plurality of compartments in which the pistons are mounted; and means for supplying motive fluid to one or more of the compartments of 65 said cylinder

2. The combination, with a chuck and its spindle, of a cylinder carried by said spindle, and having a plurality of compartments; pistons in the compartments; means connecting the pistons and chuck; and means for controlling the supply of motive fluid to one or more of the compartments of said cylinder. 70

3. The combination, with a spindle, of a chuck; a chuck-spindle; a cylinder having a plurality of compartments carried by the 75 spindle; pistons in the compartments of the cylinder; a bored shaft connecting the compartments with the chuck-spindle; and a valve in the bore of said shaft for admitting motive fluid to one or all of the compartments 80 of said cylinder.

4. The combination, with a main spindle, of a tubular chuck-spindle; a hollow shaft connected with said chuck-spindle; a compartment-cylinder surrounding the hollow 85 shaft and connected to the main spindle; a series of pistons rigid with the hollow shaft, and mounted in the compartments of the cylinder; means for supplying motive fluid to the hollow shaft; and means whereby motive 90 fluid from the hollow shaft may be supplied to one or more of said compartments.

5. The combination, with a main spindle, of a tubular chuck-spindle; a compartment-cylinder carried by the main spindle; a shaft 95 having a head connected with said chuck-spindle, and also having ports; pistons keyed to the hollow shaft, and mounted in the compartments of the cylinder; and an adjustable valve for opening and closing said ports. 100

6. The combination, with a main spindle, of a compartment-cylinder rigid therewith; a chuck-spindle; a chuck carried by said spindle; a bored shaft connected to the chuck-spindle, said shaft having ports communicating with the cylinder; and pistons 105 within the cylinder, and carried by the shaft.

7. The combination, with a chuck and its support, of a chuck-spindle; a partitubular shaft connected to the chuck-spindle, said shaft having ports; a cylinder; a main spindle to which the cylinder is secured; a series 110 of pistons secured to the tubular shaft; partitions seated in the cylinder between the pistons; a valve in the tubular shaft; and means for adjusting said valve. 115

8. The combination, with a chuck and its support, of a chuck-spindle; a partitubular shaft connected to the chuck-spindle, said shaft having ports; a cylinder; a main spindle to which the cylinder is secured; a series 120 of pistons secured to the tubular shaft; partitions seated in the cylinder between the pistons; a rod mounted in the tubular shaft; and a valve adjustable along said rod. 125

9. The combination, with a tubular live-spindle, of a chuck carried by said spindle; a sleeve connected to the chuck; a partitubular shaft having ports, said shaft being connected with the chuck-sleeve; a series of pis- 130

tons carried by said partitubular shaft; a cylinder surrounding the shaft, and secured to the live-spindle; partitions secured within the cylinder, and separating the pistons; a rod located in the tubular shaft, said rod having a threaded head acting as a plug for the bore of said shaft; a valve adjustable along said rod; a stationary collar having a groove communicating with one of the ports of the shaft; and a conduit leading from a storage-reservoir to said collar.

10. The combination, with a chuck-spindle having a slotted head, of a shaft having its end shaped to fit the slot in said head; a cylinder surrounding the shaft; a piston in said cylinder; means on the shaft for receiving the thrust of the piston; and means for supplying motive fluid to the cylinder.

11. The combination, with a chuck-spindle, of a shaft extending from said chuck-spindle; a cylinder surrounding the shaft, and having compartments; a spindle carrying said cylinder; partitions in the cylinder; pistons in said cylinder and connected to the shaft; a collar on the shaft against which one of the pistons bears; means for supplying motive fluid to the cylinder; and a spring for advancing the shaft and its connected chuck-spindle.

12. The combination, with a chuck-spindle, and chuck, of a head rigid with said spin-

die, and having a T-shaped slot, a shaft having a tenon fitted in said slot; a cylinder; a spring on the shaft located between the cylinder and tenon; a piston in the cylinder for actuating the shaft; and means for supplying motive fluid to the cylinder.

13. The combination, with a rotary chuck-spindle, of a bored shaft connected to said spindle, and having a port; a rotary cylinder surrounding the shaft; a piston in said cylinder and connected to the shaft; a stationary collar surrounding the shaft, and having a passage communicating with the port of said shaft; and means for supplying motive fluid to the passage in said collar.

14. The combination, with a tubular spindle, of a cylinder having a series of compartments rigid therewith; a chuck-spindle mounted in the tubular spindle; a shaft connected to the end of the chuck-spindle; a spiral spring surrounding said shaft between the end thereof and the end of the cylinder; pistons in the compartments of the cylinder; and means for supplying motive fluid to said cylinder.

In testimony whereof I affix my signature in presence of two witnesses.
